DEVICE FOR IMPROVING COMBUSTION IN
OIL BURNERS

Claude Siebring, George, Iowa

Application January 12, 1938, Serial No. 184,569

8 Claims. (Cl. 126—360)

My invention pertains to an improvement in oil burners.

An object of my invention is to provide, in an oil burning stove, auxiliary means for improving 5 the combustion effect in the stove.

A further object of my invention is to provide a device of this character which momentarily retards the flame or the flow of unburned gases so that the same can be then more completely mixed 10 with air to insure a more complete combustion.

A further object of my invention is to provide a simple device of this character which can be adjusted for different conditions for supplying a greater flow of air or less as desired.

15 A further object of my invention is to provide a combustion improving device which can be easily installed.

A further object of my invention is to provide a device of this character which will not get out 20 of order, due to the absence of movable parts and the like.

A further object of my invention is to provide a device of this character which can be constructed at a reasonable cost.

25 With these and other objects in view, my invention consists in the construction, arrangement and combination of the various parts of my device, whereby the objects contemplated are attained, as hereinafter more fully set forth, pointed out in my claims, and illustrated in the accompanying drawing, in which:

Figure 1 is a sectional view taken longitudinally through an oil burning stove.

Figure 2 is an enlarged sectional detail taken 35 along the lines 2—2 of Figure 1.

Figure 3 is a slightly modified form.

Figure 4 is a sectional view taken along the lines 4—4 of Figure 2, and

Figure 5 is a sectional view taken substantially 40 along the lines 5—5 of Figure 3.

I have used the character 10 to designate an upright vertical flue which includes the cap 11. A further flue 12 which acts as a chimney is spaced from the flue 10 and attached between 45 the flues 10 and 12 is a suitable tank 13 which contains the oil supply. The tank 13 includes the upwardly projecting cylindrical member 14 which is threadably engaged with the closure member 15. A small pipe 16 extends through 50 the flue wall 10 at 17 and terminates in an adjustable drip valve 18 which can be adjusted by means of the screw 19. The function of the drip valve 18 is to allow the liquid fuel 20 to drip by 55 gravity downwardly on to the fire-proof absorb-

ent material 21 which is situated at the bottom of the flue 10.

The material 21 is retained in place by means of the forwardly projecting flange member 22 which is attached to the bottom of the further 5 horizontal combustion chamber 23. The combustion chamber 23 communicates directly with the flues 10 and 12 as shown. The flame is initiated in the usual manner by lighting the absorbent member 21 upon which the oil is dripping from the drip valve 18. The flame thus initiated will burn within the flue 10 it being understood that suitable openings are provided for the air inlet and the burned gases will flow in the direction of the arrow 24 through the 15 chamber 23 and thence upwardly through the chimney flue 12. Air is fed into the burner in the usual manner through any suitable opening in the cap 11.

Normally, the burning effect is incomplete and 20 a great deal of smoke will pass upwardly through the chimney flue 12. To offset this effect, I provide in my device, a lengthened vertical rod 25 which extends upwardly and practically to the top of the flue 10. The rod 25 is attached at 26 25 between the two arcuate members 27 and 28. The arcuate members 27 and 28 form substantially approximately one-half of the circumference of the surrounding flue 10 and can be merged together with the integral flanges 29. 30 However, there is no covering member over the upper portions of the members 27 and 28 thereby leaving a free opening at 30 between such members.

Formed at the lower portion of the members 35 27 and 28 are the substantially V shaped cut-away portions 31 leaving openings at 32, with the rear member 28 including similar openings positioned in a staggered manner as shown in Figure 4.

40 In use, the points at the terminations of the V portions 31 are rested upon the asbestos or other member 21 and the rod 25 which can be slightly bent is allowed to rest against the inner wall of the flue as shown in Figure 1. The flame 45 is started in the burner and the following action takes place.

The members 27 and 28 act as a pair of baffle plates to restrict the flame from passing too rapidly into the horizontal combustion chamber 23. 50 During momentary blocking of the flame, a column of air will travel downwardly in the direction of the arrow 33 (see Figure 5) between the walls of the flue 10 and the outer member 28 and this column of air will also pass directly 55

between the arcuate baffle plates 27 and 28. As a result, a column of pure air is flowing downwardly at these points, which air will mix with the unburned vapors resulting in more complete oxidation of the flame and practically completely burning the smoke or carbon particles. The residue then passes up the chimney flue 12, which residue is clean and free from smoke.

The staggered arrangement of the V-shaped portions 31 also assists in the momentary retardation of the flame and creates an additional circulatory effect which assists in the action above described. The arrangement above described, provides for a double column of air which in this case, would be separated by the outer arcuate member 28. It will be noted that the arcuate members 27 and 28 extend upwardly a substantial distance so as to completely cover the opening of the combustion chamber 23 where 20 it merges with the flue 10.

A slightly modified form of this structure is shown in Figures 3 and 5 wherein a single baffle member 34 is used instead of two of the same. The other features are identical with the exception, however, that in the use of the single member, the column of air is not split into threee portions as in the modification shown in Figures 1, 2, and 4.

It will now be seen that I have provided a 30 device for improving combustion in oil burners, which momentarily retards the unburned flame portions in such burner to allow a more complete mixing of air therewith, and which provides features for providing an additional column or 35 columns of air which mixes with the flame at the proper point. It will be seen further that I have provided such means in a device which can be manufactured at a reasonable cost and which is simple in operation. Other advantages will 40 be readily apparent from the description.

Some changes may be made in the construction and arrangement of the parts of my invention without departing from the real spirit and purpose of my invention, and it is my intention to cover by my claims any modified forms 45 of structure or use of mechanical equivalents, which may be reasonably included within their scope.

I claim as my invention:

50 1. In a device of the class described, a housing having a vertical compartment and a horizontal compartment communicating with the bottom of said vertical compartment, a fuel tank supported by the vertical portion of said housing, a pipe 55 leading from said tank for terminating within said vertical compartment, a valve for regulating the flow of a fuel through said pipe, a spade member having notches in its bottom marginal edge loosely resting on the bottom of said vertical compartment, and an elongated handle extending from said spade to facilitate the manual placement of said spade in various positions in said vertical compartment.

55 2. In a device of the class described, a housing having a vertical compartment and a horizontal compartment communicating with the bottom of said vertical compartment, a fuel tank supported by the vertical portion of said housing, a pipe leading from said tank for terminating 60 within said vertical compartment, a valve for regulating the flow of a fuel through said pipe, a spade member having its bottom edge loosely resting on the bottom of said vertical compartment, and an elongated handle extending from 65 said member to facilitate the manual placement

of said spade member in various positions in said vertical compartment.

3. In combination with an oil burning stove of the type having a stove body including upright flues and a combustion chamber therebetween, an adjustable baffle plate adapted to be positioned within one of said upright flues and spaced from the wall thereof and adjacent to said combustion chamber, said baffle plate adapted to extend transversely to substantially 10 cover the width of said combustion chamber and said baffle plate having a plurality of lower openings, an extended vertical adjusting rod attached to the baffle plate and extending upwardly within 15 said flue for varying the draft through the combustion chamber.

4. In combination with an oil burning stove of the type having a stove body including upright cylindrical flues and a combustion chamber therebetween, an adjustable baffle plate adapted 20 to be positioned within one of said upright flues and spaced from the wall thereof and adjacent to said combustion chamber, said baffle plate having a plurality of lower openings, said baffle plate being arcuate in shape to follow substantially 25 the curvature of the flue, an extended vertical adjusting rod attached to said baffle plate and extending upwardly within said flue for varying the draft through the combustion chamber.

30 5. In combination with an oil burning stove of the type having a stove body including upright cylindrical flues and a combustion chamber therebetween, an adjustable baffle plate adapted 35 to be positioned within one of said upright flues and spaced from the wall thereof and adjacent to said combustion chamber, said baffle plate having a plurality of lower openings, said baffle plate being arcuate in shape to follow substantially 40 the curvature of the flue, and extended vertical adjusting rod attached to said baffle plate and extending upwardly within said flue for varying the draft through the combustion chamber, said openings being cut away from the lower 45 edge of said baffle plate in V-shaped formation.

45 6. In combination with an oil burning stove of the type having a stove body including upright cylindrical flues and a combustion chamber therebetween, an adjustable baffle member including an inner arcuate baffle plate and an outer arcuate baffle plate spaced therefrom, openings 50 communicating through said baffle plates from said flue into said combustion chamber, the openings of the inner baffle plate being staggered with respect to the openings of said outer baffle plate.

55 7. In combination with an oil burning stove of the type having a stove body including upright cylindrical flues and a combustion chamber therebetween, an adjustable baffle member including an inner arcuate baffle plate and an outer arcuate baffle plate spaced therefrom, openings 60 communicating through said baffle plates from said flue into said combustion chamber, the openings of the inner baffle plate being staggered with respect to the openings of said outer baffle plate, an extended vertical adjusting rod attached to said baffle plates and extending upwardly within said flue for varying the draft 65 through the combustion chamber.

65 8. In combination with an oil burning stove of the type having a stove body including upright cylindrical flues and a combustion chamber therebetween, an adjustable baffle member 70

5 including an inner arcuate baffle plate and an outer arcuate baffle plate spaced therefrom, openings communicating through said baffle plates from said flue into said combustion chamber, the openings of the inner baffle plate being staggered with respect to the openings of said outer baffle plate, an extended vertical adjusting

rod attached to said baffle plates and extending upwardly within said flue for varying the draft through the combustion chamber, said baffle plates following substantially the curvature of the flue. 5

CLAUDE SIEBRING.
